UNITED STATES PATENT OFFICE.

CHARLES E. THOMPSON, OF TROY, NEW YORK, ASSIGNOR TO HELDTITE BRUSH CO., INC., OF TROY, NEW YORK, A CORPORATION.

DESIGN FOR A HANDLE FOR SHAVING-BRUSHES.

48,050.

Specification for Design.

Patented Oct. 26, 1915.

Application filed April 23, 1915. Serial No. 23,535. Term of patent 3½ years.

To all whom it may concern:

Be it known that I, CHARLES E. THOMPSON, a citizen of the United States, residing in the city of Troy, county of Rensselaer, and State of New York, have invented a new, original, and ornamental Design for a Handle for Shaving-Brushes, of which the following is a specification, reference being had to the accompanying drawing, forming part thereof.

The figure is a plan view of a handle for shaving brushes showing my new design.

I claim:

The ornamental design for a handle for shaving brushes, as shown.

CHARLES E. THOMPSON.

Witnesses:

BEULAH CARLE,
FREDERICK W. CAMERON.
